SLUG CASTING MACHINE

Luther E. Morrison, New York, N. Y., assignor to
 Mergenthaler Linotype Company, a corpora-
 tion of New York

Application March 7, 1932. Serial No. 597,193

22 Claims. (Cl. 199—60)

This invention relates to slug casting machines, wherein printing slugs or type bars are cast in a slotted mold and delivered by an ejector advancing from the rear against the edge of the slug.

5 In these machines, the molds are adjustable in length to produce slugs of different lengths, as for printing columns or pages of different widths, and the ejector employed is therefore constructed so that it may be varied in width to correspond

10 with changes in the length of the mold slot.

For instance, as illustrated in U. S. Letters Patent to John R. Rogers, No. 967,976, there is commonly employed a composite ejector comprising a series of blades arranged edge to edge in 15 contacting relation, and suitable devices whereby any desired number of blades can be connected with the ejector slide while the others are left free and remain at rest. These ejector blades are quite thin, being made so to serve for the ejection

20 of very thin slugs, as well as of the thicker slugs.

In recent years, there has been a growing tendency to increase the thickness of the printing slugs and to such extent that the ejector above described is sometimes found to be incapable of 25 ejecting the slugs from the molds in a thoroughly satisfactory manner. Thus, it frequently happens that the ejector, because of its thinness, will embed itself in the bottom edges of the slugs and fail to eject them fully from the mold, or that,

30 because of undue resistance offered by the slugs, the ejector blades or other parts of the machine will be damaged in the act of ejection. These objections arise particularly with the larger or thicker slugs, which are of the ribbed variety, 35 i. e., comprise a solid body portion; an overhanging type-carrying portion, and a series of ribs cast on the body portion and giving support to the overhanging portion.

In the ejection of such ribbed slugs, the ejector 40 is arranged to engage only with the solid body portion, and since such portion is located well to one side of the central plane of the slugs, the latter have a tendency to cant or tilt in the mold and thereby offer greater resistance to ejection than in the case of thinner slugs whose body portions are located close to or in the central plane.

To overcome these objections, ejecting mechanism has been proposed such as that disclosed 50 in my co-pending application, Serial No. 597,192, filed March 7, 1932, or such as that disclosed in the pending application of F. C. Frolander, Serial No. 559,384, filed August 26, 1931. In the former case, separate interchangeable ejector 55 sections of different effective thicknesses are em-

ployed and means provided for selecting either section for independent use; while in the latter case, a main ejector section and one or more supplemental ejector sections are employed together with means for selecting either the main section 60 for independent use or both the main and supplemental section or sections for conjoint use. In both instances, the selection of the ejector sections is effected manually and extreme care must be observed in order to insure a correct setting 65 of the parts.

The present invention contemplates certain improvements in the above mechanisms whereby the selection of the ejector sections may be effected automatically so that they will always correspond to the selected mold. To this end, means controlled by the interchange of the molds are provided for effecting the interchange of the 70 ejector sections.

In the accompanying drawings, the invention 75 has been shown merely in preferred form and by way of example, and obviously many changes and modifications may be made therein and in its mode of application without departing from the spirit of the invention. It should be understood, 80 therefore, that the invention is not limited to any specific form or embodiment except insofar as such limitations are specified in the appended claims.

Referring to the drawings:

Fig. 1 is a side elevation, partly broken away, of an ejecting mechanism constructed and operable in accordance with one embodiment of the invention;

Fig. 2 is a detail perspective view showing the 90 connections between the individual ejector blades and corresponding slide rods;

Fig. 3 is a longitudinal section taken on the line 3—3 of Fig. 1, showing the plain section of the ejector proper in use and the actuating slide 95 in its forward position;

Fig. 4 is a front elevation partly in section of certain of the parts shown in Fig. 3;

Fig. 5 is a longitudinal section similar to Fig. 3 100 showing the ribbed or flanged section of the ejector proper in use;

Fig. 6 is a front elevation of the parts shown in Fig. 5;

Fig. 7 is a side elevation similar to Fig. 1 on a 105 slightly enlarged scale showing a second embodiment of the invention;

Fig. 8 is a longitudinal section taken on the line 8—8 of Fig. 7;

Fig. 9 is a side elevation of certain parts shown 110

in Fig. 8 and taken approximately on the line 9—9 of said figure;

Fig. 10 is a vertical section taken on the line 10—10 of Fig. 8; and

5 Fig. 11 is a detailed elevation showing the mold slide advanced and the manner of actuating the rack bars.

The mold wheel or disc A is provided with two or more molds A¹, A² (Fig. 6) of different sizes 10 or forms, either of which may be brought into use in the usual way by a manual adjustment of the disc about its axis and relative to its driving pinion (not shown). The mold A¹ (Fig. 3) is of the regular unrecessed type, being formed with a cavity 15 A³ having plain side walls and adapted for the production of thin slugs; whereas the mold A² (Figs. 5 and 6) is of the head-letter or recessed variety, being formed with a cavity A⁴, which is broken up by core sections and adapted for the 20 production of thicker ribbed slugs. If any further information is desired as to the form or construction of the molds and slugs, reference may be had to the Hall Patent, No. 665,212.

The mold wheel A (see Figs. 3 and 4) is mounted 25 for rotation upon the lateral arm A⁵ of a fore-and-aft mold slide A⁶, which is moved forwardly and backwardly in suitable guideways to carry the active mold first, or at the time of casting, into and out of contact with the matrix line, and later, 30 or at the time of ejection, into and out of operative relation to the trimming knives, all in the usual way.

The ejecting mechanism in both embodiments 35 illustrated includes the ordinary actuating slide B, which is mounted for reciprocation in the mold slide A⁶ and operated in the regular way through a connecting link B¹ from the main drive shaft of the machine.

The ejector proper, in the first or preferred embodiment (see Figs. 1 to 6, inclusive), comprises 40 two ejector sections C and D arranged side by side and supported in a frame E, which is adjustable laterally to bring one or the other of said sections into use. The ejector section C is made up of a set of blades C¹ arranged edge to edge in the regular way so as to produce collectively a composite blade of a given uniform thickness and capable of ejecting the thin unrecessed slugs from the mold A¹; whereas, the ejector D is made up of 45 a set of blades D¹, D², which differ in form so as to produce a composite blade of a greater effective thickness and capable of ejecting thicker slugs of the recessed variety from the mold A². The blades D¹ of the section D are identical with 50 the blades C¹ of the section C, while the blades D² thereof are formed with lateral ribs or flanges d of a predetermined width. As shown in Figs. 7 and 8, the blades D¹ and D² are disposed alternately one above the other and the flanges d are 55 spaced apart so as to agree with the spacing of the slug ribs cast in the mold A².

The frame E (as best shown in Figs. 1, 3 and 65 5) is slidably mounted in a pocket or recess A⁷ formed in the mold slide A⁶, and is guided in its movements by means of tongue and groove connections E¹. The movement of the frame E in one direction (toward the left according to Fig. 3) is opposed by a pair of compression springs A⁸, seated in corresponding recesses A⁹ formed in the 70 mold slide and tending to move the frame E in the opposite direction into engagement with a pair of stop screws A¹⁰, which are mounted in fixed brackets A¹¹ secured to the mold slide.

In the present instance, the adjustments of 75 the frame E are effected automatically through

means controlled by the rotary adjustments of the disc A in interchanging the molds A¹ and A². Such means (as best shown in Figs. 3, 5 and 6) consist merely of a single fore-and-aft lever O arranged alongside the frame E and operable by 80 a cam piece P secured to the recessed mold A². The lever O (see Fig. 1) is pivoted on a vertically disposed hinge pin O¹ between a pair of lugs A¹² projecting laterally from the front end of the mold slide A⁶. The shorter arm O² of the lever O is arranged in the path of the cam piece P, while the longer arm O³ thereof is arranged to engage a set screw e mounted in the contiguous side face of the frame E. The arrangement of the parts is such that, as the mold A² is brought 85 into use by a rotary adjustment of the disc A, the cam piece P is adapted to engage the arm O² of the lever O and through the longer arm O³ thereof push the frame E inwardly against the tension of the springs A⁸ to locate the ejector section D in the operative position (see Fig. 5).

The plain mold A¹, as may be observed (see Fig. 3), is devoid of a cam piece P or similar projection and will, therefore, clear and fail to actuate the lever O when, under an alternative 100 adjustment of the disc A, it is brought into use. Consequently, the frame E at such times will be pushed by the springs A⁸ outwardly into engagement with the stop screws A¹⁰ and thus locate the ejector section C in the operative position. 105

The ejector sections C and D are actuated by the ejector slide B through the medium of a single set of fore-and-aft slide rods F and a vertical adjustable bar G arranged to engage rectangular lugs f formed on the rear ends of the 110 said rods. As the section C or the section D is brought into active position, connections between the individual blades thereof and the slide rods F are established by means of lugs f¹ formed on the front ends of the said rods and corresponding notches c¹ or d¹, formed in the rear ends of the blades C¹ or D¹ and D² (see Fig. 2).

The construction of the ejector or actuating slide B, the bar G, and the means provided for adjusting said bar, are similar in all respects 115 to the corresponding mechanism used in the commercial linotype machines or as illustrated in the Rogers Patent No. 967,976, before referred to. Thus, the bar G is mounted as usual to slide vertically in a grooved guideway b formed in the 120 actuating slide B, the opposite edges of the groove snugly engaging the opposite edges of the bar so that the latter is caused to move forwardly and backwardly with the actuating slide. At its lower end, the bar G is slidably supported upon a long 125 fore-and-aft rod G¹ carried by a vertically adjustable slide G², which is operable by a hand lever G³ extended to the front of the machine.

By means of this arrangement, the bar G may 130 be set in different positions to connect the actuating slide B with any desired number of the blades in either the ejector section C or the 135 ejector section D, according to the adjusted position of the frame E or according to which section happens to be in use at the time. Consequently, when the slide B is moved forward to 140 expel the cast slug from, say, the mold A² (Fig. 5), the bar G is moved with it, its forward edge engaging the lugs f on the rear ends of the appropriate slides F, which are thus pushed forwardly and through the lugs f¹ actuate the selected ejector blades D¹ and D² (see Fig. 5). During the return stroke of the actuating slide B, a rib or shoulder b¹ formed thereon, and located in advance of the lugs f, engages the lat- 145

ter and by such engagement draws back the slides F and the connected blades D¹ and D².

Attention is now directed to Figs. 7 to 11, which are devoted to a second embodiment of the invention wherein the ejector proper is made up of a main section and a supplemental section, the main ejector section being adapted for independent use in the ejection of thin slugs, and for use conjointly with the supplemental section 10 in the ejection of the thicker ribbed slugs. The exact construction of the ejector proper and the precise manner in which the sections thereof co-operate are fully described in the Frolander application before referred to and to which reference may be had if desired. It will therefore suffice to say here that the main ejector section comprises a series of vertically disposed blades H, any selected number of which may be connected to the actuating slide B through the medium of a vertical adjustable bar J, and that the supplemental ejector section comprises a series of horizontally disposed blades I arranged alongside the main blades so as to increase the effective thickness of the ejector as a whole, and which 25 may also be connected to the actuating slide B through the medium of a supplemental bar J¹. To be more explicit, the bar J¹ is movable vertically with the bar J as the latter is adjusted but is also capable of slight vertical adjustment relatively to the bar J in making and breaking the operative connections between the individual blades I of the supplemental section and the actuating slide B.

The adjustments of the bar J are effected manually and in the usual way by the operation of a hand lever J², but the adjustments of the bar J¹, according to the present invention, are effected automatically through a train of connections controlled by the interchange of the molds A¹ and A². These connections (see Fig. 7) include a long fore-and-aft rock shaft J³ upon which both bars J and J¹ receive support, and which is mounted in a vertical slide J⁴ controlled by the hand lever J². As shown best in Fig. 7, the bar J at its lower end is connected to a short sleeve J⁵ which is splined to the shaft J³ and adapted to slide back and forth thereon with the bar J during the reciprocation of the actuating slide B.

The sleeve J⁵ (see Figs. 7 and 9) is provided 50 with a cam or eccentric J⁶ for actuating the supplemental bar J¹ and upon which the lower end of said bar is directly engaged. A spring j seated against a lug on the bar J resists the upward movement of the bar J¹ as effected by the cam J⁶, and holds it resiliently engaged therewith. Thus, 55 by turning the shaft J³ in opposite directions the bar J¹, through the sleeve J⁵ and eccentric J⁶, will be raised and lowered to connect and disconnect the supplemental set of blades I with and 60 from the actuating slide B.

The rock shaft J is operated by a pair of vertically disposed rack bars K, K¹, arranged to mesh at opposite sides with a pinion J⁷ secured to the front end of the shaft, and which rack bars are mounted to reciprocate in suitable guideways K² and K³. The two rack bars K, K¹ are actuated 65 by a cam plate L which is movable forwardly and backwardly with the mold slide A⁶ and arranged to engage in one or the other of notches k¹, k², formed in the upper ends of the rack bars. As 70 best shown in Figs. 8 and 10, the cam plate L is supported from a block L¹ upon a pair of pins L², which project beyond the cam plate so as to carry small compression springs l¹. The block L¹ (see 75 Fig. 10) is slidably mounted in a suitable sup-

port M and is slotted longitudinally to accommodate a cam L³ against which the cam plate L is resiliently maintained under the tension of the springs l¹. The cam L³ is splined to a vertically disposed rock shaft L⁴ which is passed through the block L¹ and journaled at its opposite ends in fixed bearings L⁵ projecting from the face of the mold slide A⁶.

With this arrangement, the cam plate L may be adjusted facewise by a partial rotation of the shaft L⁴ and the cam L³, so as to stand in line with the notch k¹ or the notch k² of the rack bars K, K¹, respectively; then, as the mold slide A⁶ is advanced preparatory to ejection, the cam plate L through its engagement with the upper wall of one of these notches is adapted to lift the corresponding rack bar K or K¹, which in turn will rotate the fore-and-aft shaft J³ and through the eccentric J⁶ adjust the supplemental bar J¹ upwardly or downwardly according to the particular rack bar actuated. If the cam plate L happens to stand in the position shown in Fig. 8 and in line with the rack bar K¹, the selecting bar J¹ will be raised by the eccentric J⁶ as the mold slide is advanced and thus connect the supplemental section I of the ejector to the actuating slide B¹; whereas, if the cam plate L occupies its other position of adjustment (indicated by the dotted lines in Fig. 8) and in line with the rack bar K, the bar J¹ will be lowered by the spring j under 100 the control of the eccentric J⁶ and thus disconnect the supplemental section from the actuating slide.

It may be stated at this point that in order to permit the adjustments of the supplemental bar J in any adjusted position of the main bar J, the rack bars K, K¹, and their actuating means (including the cam plate L and the block L¹) obtain support from the fore-and-aft rock shaft J³, the latter (as shown best in Fig. 7) being provided with a bracket member J⁸ and a long vertical rod J⁹ secured to said member. The rod J⁹ is guided in fixed bearings J¹⁰ and carries at its upper end the support M and the upper guideways K² for the rack bars, which are secured to 115 the support M. The lower guideways K³ are formed on the bracket member J⁸ which is extended forwardly for this purpose (see Fig. 7).

To complete the train of connections and bring about the adjustments of the bar J¹ automatically as proposed, the rock shaft L⁴ is actuated by a vertically disposed lever R which is controlled by a cam piece Q secured to the mold A². The lever R is pivoted at r to the mold slide and arranged in close relation to the back of the mold. The shorter arm R¹ of the lever R is formed with a beveled cam surface r¹ located in the path of the cam piece Q, and the longer arm R² thereof is connected by a link R³ to a crank arm L⁶ fast to the vertical rock shaft L⁴. A pull spring R⁴, 120 connected to the longer arm of the lever R and anchored to the mold slide, tends to move the lever into engagement with a stop pin r² and through the link R³ turn the shaft L⁴ in a clockwise direction. However, as the mold A² is brought into operative position, the cam piece Q is adapted by its engagement with the beveled surface r¹ to move the lever R away from the stop pin against the tension of the spring R⁴, and 125 through the link R³ turn the rock shaft L⁴ in the opposite direction. At such times, the cam plate L (as shown in Fig. 8) will be adjusted by the cam L³ into position to raise the rack bar K¹ and through the fore-and-aft shaft J³ connect 130 135 140 145 150

the supplemental blades I of the ejector to the actuating slide B so that they may be used jointly with the main blades H.

The regular molds A¹ are devoid of the cam piece Q, and hence when they are substituted for the molds A², the pull spring R⁴ will be allowed to act and, as a result, the cam plate L will be adjusted under the control of the cam L³ into a position to raise the other rack bar K and through the shaft J³ disconnect the supplemental blades I from the ejector slide B so that the main blades H may be used alone.

Having thus described my invention, what I claim is:

15. 1. In a slug casting machine, the combination of a plurality of molds for producing slugs of different thicknesses, means for selecting one or another of said molds for use, a slug ejecting mechanism including an ejector proper variable in thickness, and automatic means for varying the effective thickness of the ejector according to the particular mold in use.
20. 2. In a slug casting machine, the combination of a plurality of molds for producing slugs of different thicknesses and interchangeable in operative position with each other, a slug ejecting mechanism including an ejector proper variable in thickness, and means controlled by the interchange of the molds for varying the effective thickness of the ejector, as required.
25. 3. A combination as specified in claim 1 including separate means for varying the effective width of the ejector.
30. 4. In a slug casting machine, the combination of a plurality of molds for producing slugs of different thicknesses and interchangeable in operative position with one another, slug ejecting mechanism including a plurality of distinct ejector sections of different effective thicknesses and also interchangeable in operative position with each other, and means controlled by the interchange of the molds for effecting a corresponding interchange of the ejector sections.
35. 5. In a slug casting machine, the combination of a plurality of molds for producing slugs of different thicknesses and interchangeable in operative position with one another, slug ejecting mechanism including an ejector proper having a plurality of ejector sections of different effective thickness, a movable supporting frame for said sections, and means controlled by the interchange of the molds for adjusting the support to bring the appropriate ejector section into use.
40. 6. In a slug casting machine, the combination of a plurality of molds for producing slugs of different thicknesses and interchangeable in operative position with one another, slug ejecting mechanism including an ejector proper having two composite ejector sections of different effective thicknesses, means controlled by the interchange of the molds for selecting the appropriate ejector section, an actuating slide common to both sections, and adjustable means for connecting the selected or active section to the actuating slide.
45. 7. In a slug casting machine, the combination of a plurality of molds for producing slugs of different thicknesses and interchangeable in operative position with one another, slug ejecting mechanism including an ejector proper having two composite ejector sections of different effective thicknesses, means controlled by the interchange of the molds for selecting the appropriate ejector section, and means for varying the effec-

tive width of the selected section to correspond to the length of the slot in the active mold.

8. In a slug casting machine, the combination of a plurality of molds differing in form so as to produce plain and ribbed slugs, a mold carrier adjustable to bring any selected mold into use, slug ejecting mechanism comprising two ejector sections differing in form to correspond to the respective molds, and means controlled by the adjustments of the carrier for selecting the appropriate ejector section.

9. In a slug casting machine, the combination of molds of different forms and interchangeable in operative position with each other, slug ejecting mechanism including an ejector proper having two ejector sections differing in form to correspond to the respective molds, an adjustable supporting frame whereon said sections are slidably mounted, and means arranged to cooperate with the individual molds for adjusting the supporting frame automatically.

95. 10. A combination as specified in claim 9, characterized by the fact that the said supporting frame is moved in one direction by a spring and in the opposite direction by a lever controlled by a cam piece secured to one of the molds.

100. 11. In a slug casting machine, the combination of a plurality of molds for producing slugs of different thicknesses and interchangeable in operative position with each other, a slug ejecting mechanism including an ejector proper having a main ejector section and a supplemental ejector section arranged alongside thereof to increase the effective thickness of the ejector as a whole, and automatic means controlled by the interchange of the molds for selecting either the main ejector section alone, or both the main and supplemental sections, as required.

105. 12. In a slug casting machine, the combination of a plurality of molds for producing slugs of different thicknesses and interchangeable in operative position with each other, a slug ejecting mechanism including an ejector proper having a main ejector section and a supplemental ejector section arranged alongside thereof to increase the effective thickness of the ejector as a whole, an actuating slide common to both ejector sections, means for connecting the main section to said slide, and automatic means controlled by the interchange of the molds for connecting and disconnecting the supplemental section to and from the slide, as required.

110. 13. In a slug casting machine, the combination of a plurality of molds for producing slugs of different thicknesses and interchangeable in operative position with each other, slug ejecting mechanism comprising a main set of ejector blades, a supplemental set of ejector blades, a main bar adjustable to connect any selected number of blades in the main set to the actuating slide, a supplemental bar carried by the main bar and adjustable relatively thereto to connect a corresponding number of blades in the supplemental set to the actuating slide, means operable at will for effecting the adjustment of the main bar, and automatic means controlled by the interchange of the molds for effecting the adjustments of the supplemental bar.

115. 14. In a slug casting machine, the combination of a plurality of molds for producing slugs of different thicknesses and interchangeable in operative position with each other, a mold slide, slug ejecting mechanism comprising a main set of ejector blades, a supplemental set of ejector blades arranged alongside thereof, an actuating

19. In or for a slug casting machine, a slug ejecting mechanism including in combination an ejector proper having two composite ejector sections of different effective thicknesses, automatic means for selecting either section for independent use, and means for varying the effective width of the active section.
20. In or for a slug casting machine, a slug ejecting mechanism including in combination two sets of ejector blades, automatic means for selecting either set for independent use, an actuating slide common to both sets, and manually controlled means for connecting different selected numbers of blades of the active set to the said slide.
21. In or for a slug casting machine, a slug ejecting mechanism including in combination a main ejector section, a supplemental ejector section arranged alongside thereof to increase the effective thickness of the ejector as a whole, and automatic means for selecting the main ejector section for independent use or for selecting both the main and supplemental sections for use conjointly, as required.
22. In or for a slug casting machine, a slug ejecting mechanism including in combination a main ejector section, a supplemental ejector section arranged alongside thereof to increase the effective thickness of the ejector as a whole, a common actuating slide, manually controlled means for connecting the main section to said slide, and means operable automatically for connecting and disconnecting the supplemental section to and from the actuating slide, as required.
- LUTHER E. MORRISON.
